UNITED STATES PATENT OFFICE.

JESSE D. SMITH, OF NEW YORK, N. Y.

FUEL-CONTROLLING DEVICE FOR MOTOR-VEHICLES.

1,273,283.

Specification of Letters Patent.

Patented July 23, 1918.

Application filed January 2, 1918. Serial No. 210,075.

To all whom it may concern:

Be it known that I, JESSE D. SMITH, a citizen of the United States, residing at New York city, in the county of New York and State of New York, have invented certain new and useful Improvements in Fuel-Controlling Devices for Motor-Vehicles, of which the following is a specification.

This invention relates to fuel controlled devices for motor-vehicles and more particularly to valved devices of this character adapted to be interposed at some point in the fuel supply pipe for controlling the supply of liquid fuel to the motor.

The main object of the invention is to provide simple and efficient valved means so constructed as to form a continuous passage from the gas tank to the motor of a combustion engine only when properly set in a predetermined position, knowledge of which is available only to the rightful operator.

Another object is to provide a valve of the type set forth with permutation means whereby the position of the valve may be varied at will, and whereby a person having knowledge of the combination may easily manipulate the valves to cause them to assume the proper position without the use of tools.

Another object is to so construct a valve of the class described as to render it capable of being cheaply manufactured, readily installed and durable and efficient in operation.

With the foregoing and other objects in view, which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings:—

Figure 1 represents a side elevation of a controlling device constructed in accordance with this invention and shown in operative position, the support on which it is mounted being shown in section.

Fig. 2 is a top plan view thereof,

Fig. 3 is a longitudinal vertical section taken on the line 3—3 of Fig. 2,

Fig. 4 is a view similar to Fig. 1 showing a slightly modified form of the invention,

Fig. 5 is a detail longitudinal section through two of the valves of the device shown in Fig. 4, and

Fig. 6 is a horizontal section taken on the line 6—6 of Fig. 5.

In the embodiment illustrated in Figs. 1 to 3, the device constituting this invention comprises a supporting casing 1 closed at its ends and open at its sides and which is bolted to a suitable support, here shown in the form of a car floor F, said casing depending from the lower face thereof and having mounted therein a plurality of valves 2. These valves 2 are preferably arranged in longitudinal alinement and any desired number of them may be employed, four being here shown, all of which are exactly alike and hence one only will be described in detail. Each of these valves 2 comprises a cylindrical casing 3 which rests on the bottom 4 of the supporting casing 1 and may be secured thereto in any suitable manner. These cylindrical valve casings 3 are closed at their upper ends by removable caps 5 which have central openings 6 therein for the passage therethrough of stems 8 carried by the valve members 7. These members 7 may be solid as shown in Fig. 3 but need not necessarily be so formed, and each has a stem 8 leading through the passage or opening 6 in the cap 5 and extending upward through the floor F of the car, the upper ends of said stems projecting some distance above the floor F, although they need not necessarily be so disposed, the only object in having them above the floor is to conveniently position them for actuation by the driver.

The valve members 7 each has a bore 9 extending transversely therethrough, preferably at an angle to the horizontal, the inlet end of which is at a higher elevation than its discharge end. These bores 9 when the valves are in a certain position are designed to register with inlet and discharge openings 10 and 11 respectively formed in each valve casing 3 as is shown clearly in Fig. 3. The fuel supply pipe P in which this controlling device is interposed enters the inlet 10 of one end valve as is shown clearly in Figs. 1 and 3 and the discharge or outlet 11 of the other end valve is connected with the portion of the pipe P which leads

to the motor, the portion connected with the inlet at the other end of the series leading from the gas tank and is preferably equipped with a cock 12 so that gas may be cut off entirely from the controlling device when desired for repairs or other purposes. The cylinders of the series are connected with each other by a plurality of inclined pipes or conduits 13, each pipe being in registration at its front end with the discharge or outlet 11 of one valve casing 3 and at its rear end with the inlet of the adjacent valve casing. It is thus seen that when the valves are positioned so as to bring their bores 9 into register with the inlets and outlets of the casings 3, said bores will also communicate with the conduits 13 and with the pipe P, thus forming a zigzag passage from the pipe portion which connects with the cylinder at the front of the series and that portion which connects with the cylinder at the rear thereof.

A wear plate 14 is mounted on the upper face of the floor F through which the stems 8 of the valves are designed to pass and supported above this plate on uprights 15 rising from the ends of said wear plate is a transparent cover 16 screwed or otherwise secured to said supports, it being here shown pivotally mounted at one end thereon and having a lock 17 at its opposite end for holding it in operative position. This transparent cover plate 16 is mounted in a suitable frame 18 and is here shown rectangular in form, being comparatively narrow in width for a purpose presently to be described.

Carried by each of the valve stems on its upper end is a dial 19 which while here shown rectangular in form may be of any suitable or desired configuration and as shown is attached to the valve stem by a screw 20. These dials 19 perform the double function of turning members for the valve bodies 7 and to contain peripheral characters 21, any desired number of which may be used and which are designed to form a safeguard against an unauthorized placing of the valve bores 9 in alignment with the casing inlets and outlets, since the operator of the valves can only be assured that all of the valve bodies 7 are in the necessary alignment in which fuel is permitted to flow through the bores 9 and conduits 13 by the position assumed by the dials 19 with respect to the transparent cover plates 16, the characters on the dials having been so placed that their position relative to this cover plate will be coincident with and in alignment with the valve bores 9 with the casing inlets and outlets as may be readily determined at the time of installation of the device.

It will thus be seen that when the driver leaves his vehicle he need only rotate two

or more of the permutation dials 19, to a greater or less extent in order to shut off the supply of fuel from the motor and also to jumble up the number to which the whole series of valves must be set in order to restore the supply of fuel. Under these conditions no person other than the driver can reopen the control device except by very protracted trials.

It is in the power of the driver to change the combination number for opening the valves as many times as he likes in the course of a day so that all possibility of unauthorized persons learning the combination and operating the valves is obviated.

In the form of the invention shown in Figs. 4 to 6 the construction is very similar to that shown in the above described figures except that the conduits 13' instead of being in the form of obliquely disposed pipes as in Figs. 1 to 3 are shown step-shaped, the lower member 22 of which communicates with the outlet opening of one valve casing 3 while the upper portion 23 thereof communicates with the inlet opening of the adjacent valve casing and which is disposed in a plane above its outlet as is shown clearly in Fig. 5.

The portion of the pipe P which connects the control device with the gas tank is here shown provided with an ordinary coupling 24 instead of having the cock 12 as shown in the other figures. In view of the similarity between these two forms of the invention it is not deemed necessary to further describe this form in detail.

It will thus be seen that with either form of the control device the driver may quickly cut off the supply of gas to the carburetor and thereby insure the safety of his vehicle from the use of unauthorized persons.

From the foregoing description, taken in connection with the accompanying drawings, the advantages of the construction and of the method of operation will be readily apparent to those skilled in the art to which the invention appertains and while I have described the principle of operation of the invention together with the device which I now consider to be the best embodiment thereof, I desire to have it understood that the device shown is merely illustrative and that such changes may be made as are within the scope of the claimed invention.

I claim:—

In a fuel controlling device a plurality of valves in intercommunication, a valve stem for each valve, a plate having openings to receive the stems, an angular plate secured to each stem utilizable conjunctly as a handle and dial, upstanding members at the ends of the first plate, a cover plate having a narrow opening hingedly connected to one upstanding member, a transparent plate

mounted in said narrow opening, and means for locking the free end of the cover plate to the other upstanding member, whereby the angular plates may be arranged to expose certain characters for observation through the narrow opening of the cover plate whereby to communicate the valves.

In testimony whereof I affix my signature in presence of two witnesses.

JESSE D. SMITH.
